(57) **CLAIM**

The ornamental design for a domestic food slicer, as shown and described.

DESCRIPTION

FIG. 1 is a front, top right side perspective view showing my new design;

FIG. 2 is a right side elevation view thereof;

FIG. 3 is a top plan view thereof;

FIG. 4 is a front elevation view thereof;

FIG. 5 is a front, top right side perspective view of another embodiment of my new design;

FIG. 6 is a right side elevation view thereof;

FIG. 7 is a top plan view thereof;

FIG. 8 is a front elevation view thereof;

FIG. 9 is a front, top right side perspective view of another embodiment of my new design;

FIG. 10 is a right side elevation view thereof;

FIG. 11 is a top plan view thereof; and,

FIG. 12 is a front elevation view thereof.

The elements shown in broken lines form no part of the claimed invention.
